SUPPLY OF AMMUNITION TO FREELY ROTATABLE GUN TURRETS

Evelyn Cecil Muschamp d'Assis-Fonseca and John Wotton, Bristol, England, assignors to The Bristol Aeroplane Company Limited, Bristol, England, a British company

Application December 18, 1945, Serial No. 635,658
In Great Britain December 19, 1944

7 Claims. (Cl. 89—33)

1

This invention concerns improvements in or relating to gun turrets and to the supply of ammunition thereto.

The invention relates to gun turrets of the kind which are capable of continuous rotation in either/or both directions of traverse.

In gun turrets of this kind the supply of ammunition is usually carried within the turret so that it rotates therewith. Although in this way no twist is imparted to the belt upon rotation of the turret the quantity of ammunition carried is governed by the space available instead of by operating requirements. Moreover, disposing the ammunition in the turret increases the weight of the installation so that traversing motors of greater power are required.

By disposing the ammunition supply outside the turret these disadvantages are overcome. Furthermore, when the turret is carried in an aircraft the ammunition supply may be disposed at about the centre of gravity of the aircraft so that the latter is not unduly affected by the quantity of ammunition provided. With a view to overcoming the above disadvantages it has heretofore been proposed to provide for feeding an ammunition belt into the interior of a rotatable gun turret from a storage outside of said turret the ammunition belt being led into the turret by a path which lies along the axis of rotation of the turret, the ammunition belt passing through a pair of spaced guides one of which is fixed and the other of which is rotatable with the turret the arrangement being that rotation of the turret causes twisting of the belt in, and only in, the length of the belt between the two guides. With this proposed arrangement the degree of rotation of the turret is limited by the amount of twisting which may be imparted to the belt between the two guides so that the proposed arrangement is impracticable when the gun turret is of the kind above set forth which is capable of continuous rotation in either or both directions of traverse.

The present invention has for its principal object to provide a gun turret of the kind set forth in which the ammunition supply is outside the turret and in which the twist imparted to the belt is automatically eliminated.

According to the present invention a gun turret of the kind set forth is characterised in that a belt of ammunition which passes from a source of supply outside the turret into said turret is twisted with rotation of the latter, said twist being resisted by means which is permitted to return the belt when the belt has been twisted.

2

through a predetermined angle or to a predetermined position.

According to another aspect of the invention means for feeding an ammunition belt into a turret of the kind set forth is characterised in that the ammunition belt approaches the turret along a chute which is twistable from a datum position against the action of a restraining agent and disengageable means is provided to couple said supply chute to the turret for rotation therewith, said coupling means being automatically disengaged when said chute has been twisted through a predetermined angle from its datum position whereby the supply chute is returned to its datum position and said coupling means is automatically re-engaged.

According to another feature of the present invention means for feeding an ammunition belt to a turret of the kind set forth comprises an ammunition chute carried by and rotatable with the turret, a supply chute for leading an ammunition belt to the turret (said supply chute which is capable of being twisted through a predetermined angle from a datum position being spaced from the turret chute to accommodate a portion of the ammunition belt therebetween) means for returning the supply chute to its datum position and disengageable means for coupling the turret-end of the supply chute to the turret.

A specific embodiment of the present invention will now be described by way of example with reference to the accompanying drawings, whereof:

Figure 1 is a diagrammatic view showing a gun turret in accordance with this invention located on the upper surface of the fuselage of an aircraft;

Figure 2 is a sectional elevation of the belt aligning mechanism;

Figure 3 is a section on the line 3—3 of Figure 2, and

Figure 4 is a view of a portion of the belt of ammunition which is fed into the turret.

Referring to Figure 1: the gun turret is generally indicated by the reference numeral 5 and is mounted on the upper surface of the fuselage 6 of an aircraft, the turret being supplied with ammunition from a source of supply 7 located outside the turret and within the fuselage. A single belt of ammunition passes from the source of supply 7 by means of chutes 8 and 11 to the turret 5 and entering the latter passes upwardly towards a cannon machine gun 9. The chute 8 extends from the ammunition box 7 to beneath the turret 5 where it is anchored (as at 10) to the

fuselage 6 at a point disposed on the axis of rotation of the turret. The chute 11 which is capable of being twisted with rotation of the turret extend along said axis from the anchor point 10 to the bottom of the turret: this is the supply chute mentioned above. The ammunition belt is conveyed to the turret and after passing into the latter is conveyed along another chute (the turret chute 12) to the machine gun 9.

The present invention contemplates permitting the supply chute 11 (and hence the ammunition belt therein) to be twisted by the turret 5 about its anchorage 10 from a datum position through a complete circle whereupon the chute 11 is automatically untwisted and brought back to said datum position. For convenience it will be assumed that said datum position is that in which the long axis of the rounds of ammunition in the supply chute 11 point fore-and-aft of the aircraft. When the chute 11 is in this datum position the gun 9 will also be pointing fore-and-aft of the aircraft, the turret 5 being in its datum position. Figure 1 shows this arrangement in which the rounds of ammunition in the chute 11 are in their datum position pointing fore and aft, the gun 9 being similarly directed.

The construction and operation of the belt-aligning device will now be described with reference to Figures 2 and 3. The upper end of the supply chute 11 is attached to a guide 13 which is carried by a disc 14 rotatably mounted in the bottom of the turret. The disc 14 is co-axial with the axis of rotation of the turret 5 and is carried upon anti-friction bearings 15 disposed between the disc and the floor 16 of the turret. A drum 17 is bolted (as at 18) to the disc 14 and extends downwardly therefrom beneath the turret. The drum 17 is provided with a bracket 19 which carries a pair of rollers 20, while a platform 21 secured to the fuselage carries a pair of co-operating rollers 22. A steel cable 23 passes between the pair of rollers 20, 22 to engage at one end with a spring 24 mounted upon the platform 21 and at the other end with the rollers 20 by means of the nipple 25. The spring 24 is pretensioned to a certain extent so that a pull is always transmitted by cable 23 to the rollers 20 and hence to the drum 17 thereby tending to maintain the latter in a predetermined position. As a consequence the disc 14, guide 13 and the upper end of the supply chute 11 are urged towards this predetermined position, which is the datum position referred to above. In the event that the disc-drum unit 14, 17 is rotated in either direction the spring 24 is compressed, the cable 23 passing over the pulleys 22 and between the pulleys 20 during rotation thereof with a minimum of friction and the spring will urge the disc-drum unit to return to the datum position.

The drum 17 is formed with an arcuate slot 26 with which there is associated a plunger 27 carried by the floor 16 of the turret 5. The plunger 27 is urged by spring 28 towards the drum 17 so as to enter into the slot 26 and carries a roller 29 which is capable of co-operating with a ramp 30 secured to the platform 21. It will be appreciated that when the plunger 27 passes through the arcuate slot 26 rotation of the turret 5 will be transmitted from the floor 16 thereof to the plunger 27 which, engaging with either end of the arcuate slot, imparts rotation to the drum 17 and hence to the disc 14, guide 13 and the supply chute 11. Such rotation will be resisted by the spring 24. When, during rotation

of the turret, the roller 29 is brought into engagement with the ramp 30 the plunger 27 will be withdrawn from the arcuate slot 26 and as a consequence the turret 5, floor 16 and plunger 27 are free to rotate independently of the drum 17, disc 14 and supply chute 11. As a consequence, the disc-drum unit 14, 17 is capable of being returned to its datum position by the spring 24 irrespective of the rotation which is being imparted to the turret 5.

When the supply chute 11 is in its datum position so that the rounds of ammunition therein and the gun 9 points fore-and-aft of the aircraft the roller 29 is at the crest of the ramp 30 and plunger 27 is in its retracted position and midway between the extremities of the arcuate slot 26. Upon rotation of the turret 5, in either direction, the roller 29 is moved down the ramp 30 and the plunger 27 moves towards the drum 17. When the roller 29 disengages the ramp 30 the plunger 27 has entered the slot 26 and is therefore in a position to engage with the extremities of the slot. Thereafter, further rotation of the turret brings the plunger 27 into engagement with one end of slot 26 and as a consequence disc 14 is carried around with the turret. When the turret describes a complete circle from its datum position the roller 29 is once more at the crest of the ramp 30 with plunger 27 disengaged from slot 26. Upon disengagement of the plunger 27 from the slot 26 the disc 14 and supply chute 11 are rotated by return spring 24 relatively to the turret 5 back to the datum position of the chute. This position is shown in Figures 2 and 3. It will be clear from Figure 3 that when the supply chute 11 has been re-aligned as described, the roller 29 and plunger 27 have been returned to the positions indicated above so that with continued rotation of the turret the plunger 27 is again brought into engagement with the drum 17 by entering slot 26.

For the effective operation of the device described above it is essential that at the end of a re-aligning operation the slot 26 be brought to a position in which the ends thereof are disposed one on each side of the axis of the plunger 27 irrespective of any movements of the turret which may take place away from its datum position during that time in which the supply chute 11 is being untwisted. For instance, at the moment when the plunger 27 is withdrawn from the slot 26 by the action of ramp 30 to effect re-alignment, the turret which has been rotating in one direction up to its datum position (at which this release is effected) may at the moment of release commence rotation in the opposite direction. Under these circumstances the plunger 27 is moving away from the datum position to which the drum 17 is being returned. To ensure that in this, and in all other cases, the slot 26 assumes a position such that it will definitely be re-engaged by the plunger 27 after the supply chute 11 has been returned to its datum position, the length of the arcuate slot 26 is selected so that the turret at its maximum rate of traverse will move through less than half said length in the time which is required for the supply chute to be returned to its datum position.

The plunger 27 will enter the slot 26 when the turret has moved over a portion of the arc defined thereby and it will only be after further rotation of the turret in the same direction that the plunger will engage with one end of the slot

26 and commence imparting a twist to the chute 11.

The turret chute 12 which conveys the ammunition belt to the gun 9 is secured at its lower end to a guide 31 which is supported by a structure 32 carried by the floor 16 of the turret 5. As is clear from Figure 2 the turret chute 12 is coaxial with the supply chute 11 and the guide 31 is spaced from the guide 13. During rotation of the turret 5 from its datum position a twist is imparted to the ammunition belt lying within the supply chute 11 whilst the portion of the ammunition belt within the turret chute 12 remains untwisted and the portion of the belt between the guides 13 and 31 has imparted to it only the slight twisting due to movement of the turret to bring the plunger 27 into engagement with one end of the arcuate slot 26. However, when realignment takes place the consequent untwisting of the supply chute 11 subjects the length of belt between the guides 13 and 31 to a corresponding twist of one complete revolution. It is therefore necessary to enable rotation to take place between that portion of the belt associated with the supply chute 11 and that portion of the belt associated with the turret chute 12. To this end the belt (which is generally indicated by the reference numeral 33) comprises rounds of ammunition 34 which are connected together by links 35 that permit adjacent rounds of ammunition to be twisted relative to each other through a complete turn. The links 35 which permit this relative movement are of known construction and each comprises a single-arm clip 36, a double-arm clip 37 and a rivet or the like 38 which secures the two clips together and permits pivotal movement thereof (see Figure 4).

Since the guide 13 associated with the rotatable disc 14 and the guide 31 associated with the turret chute 12 are spaced apart (as shown in Figure 2) when the supply chute 11 is re-aligned that portion of the ammunition belt which is associated with said chute will be rotated through a complete circle relatively to that portion of the ammunition belt which is associated with the turret chute 12 this being permitted by the connection of the single and double-arm clips by the rivet 38.

Since the rate of ammunition supply to the turret 5 is high compared with that at which the supply chute 11 is realigned, a circumstance may arise in which the portion of the ammunition belt 33 associated with guide 13 is drawn into engagement with the guide 31 before realignment is completed. In such an event the round of ammunition lying somewhat transversely of the rectangular mouth of the guide 31 would press against the lower edge thereof and prevent the ammunition belt from passing to the gun 9. To prevent this occurrence a firing cut-out switch 40 is provided in the circuit to the electric firing gear of the gun 9, the said switch being operated by a trigger 41 carried by the plunger 27. The arrangement is that the switch 40 is opened when the trigger 41 is moved away therefrom and this occurs when the roller 29 is brought into engagement with the ramp 30 so that the firing circuit is broken and the belt of ammunition 33 ceases to be drawn towards the gun 9 and across the space between the guides 13 and 31 when the supply chute 11 is freed from the turret 5 and during its return to the datum position. In the event that there is associated with the gun 9 an electrically driven stripper mechanism of known construction for separating the links 35 from the rounds of ammunition the switch 40 will also be

associated with the electric driving motor for the stripping mechanism so that when realigning is commenced the firing circuit of the gun is interrupted and simultaneously the electric motor of the stripper mechanism is rendered inoperative.

To ensure that the ammunition belt is stopped in such a position that a rivet 38 lies within the space between the guides 13 and 31 the stripper mechanism incorporates a locking device which is spring urged to its locking position and is solenoid operated to its retracted position. The solenoid is in the circuit of switch 40 so that when the latter is actuated the locking device is urged to its operative position—where it halts the stripper mechanism with the belt in the selected position relative to guides 13 and 31.

We claim:

1. A device of the kind set forth comprising a gun turret, a belt of ammunition, a source of supply of ammunition disposed outside the turret, chute means for conveying the ammunition belt from said source of supply into said turret, means for twisting the chute with rotation of the turret, means for resisting the twisting of said chute and for returning the chute to its untwisted position when the chute has been twisted through a predetermined angle.

2. Means for feeding an ammunition belt into a turret of the kind set forth characterised in that the ammunition belt approaches a turret along a supply chute which is twistable from a datum position against the action of a restraining agent and disengageable means is provided to couple said supply chute to a turret for rotation therewith, said coupling means being automatically disengaged when said supply chute has been twisted through a predetermined angle from its datum position whereby the supply chute is returned to its datum position and said coupling means is automatically re-engaged.

3. Means for feeding an ammunition belt to a turret of the kind set forth comprising a turret-ammunition chute carried by and rotatable with a turret, a supply chute for leading an ammunition belt to a turret, said supply chute being capable of being twisted through a predetermined angle from a datum position and being spaced from the turret chute to accommodate a portion of the ammunition belt therebetween, means for disengageably coupling the turret-end of the supply chute to a turret and means for returning the supply chute to its datum position.

4. Ammunition-belt feeding means as claimed in claim 3 in which the chute-returning means comprises a spring or the like which urges said supply chute to maintain its datum position.

5. Ammunition-belt feeding means as claimed in claim 3 wherein said disengageable coupling means comprises a catch member carried by the turret, a pair of spaced catches associated with the chute, either of said catches being engageable by the catch member to rotate the supply chute by the turret and means carried by the turret mounting engageable by said catch member to disengage the latter from said catch at the datum position of the supply chute.

6. Ammunition-belt feeding means as claimed in claim 3 in which said turret-ammunition-chute is spaced from said supply chute by the length of belt between a pair of adjacent links of ammunition belt.

7. Ammunition-belt feeding means as claimed in claim 3 in which there is provided a switch which is operated by said means while the sup-

ply chute is uncoupled from the turret to interrupt the firing of the gun.
